Louis Necho
ATTORNEY.

UNITED STATES PATENT OFFICE

RUDOLF E. ZERUNEITH, OF CAMDEN, NEW JERSEY

ANVIL BLADE FOR WIRE STITCHING MACHINES

Application filed April 23, 1931. Serial No. 532,383.

My invention relates to a new and useful anvil for use in connection with wire stitching or stapling machines which is so devised as to permit stapling of the flaps of a folding paper or card board box after such box has been formed and after the contents of the box have been placed therein to prevent the unauthorized and surreptitious exchange of the contents of the box after it has been packed and sealed.

As an illustration of the purpose of my invention, I will refer to the conventional package used for shipping radio tubes from manufacturers to dealers, which boxes consist of a generally rectangular package having suitable cushioning stuffing and containing radio tubes. When a purchaser returns a defective tube to the dealer or when the customer "trades in" a set of tubes, the dealer, unless he is scrupulously honest, will withdraw the new tubes from the original package and put the returned or "traded in" tubes in said package with a view of passing such tubes on to an unsuspecting, less discriminating or ignorant customer. This substitution of imperfect goods is by no means limited to radio tubes and is more or less prevalent in other fields also.

In order to guard against such deception, manufacturers of products which are susceptible to substitution have resorted to the use of paper seals so glued on the package that the package must be broken before access can be had to the contents of the package. This practice was not sufficient for the reason that with patience the seal could be "un-glued" or otherwise removed and put back in position and for the further reason that the breaking of the seal can always be explained by rough handling of the package, etc.

It is therefore the object of my invention to provide means for permanently sealing the ends of a package with a wire stitch which cannot possibly be removed without doing irreparable damage to the body of the package and which, in fact, necessitates the complete tearing apart of the end flaps of a package before its contents can be removed. The method of using my invention is fully described and claimed in my copending appli-

cation Serial No. 532,382, filed April 23, 1931, this application being directed to the anvil blade by which my invention is carried out.

To the above ends my invention consists of a novel anvil blade adapted to form part of a wire stitching or stapling machine, said blade having a flat hooked end portion which is adapted to engage the end flaps of a box when said end flap is being inserted in position to close the end of the box, and to support said box and flap while a stitch is put through said end flap and the juxtaposed wall of the box.

My invention further consists of various other novel features of construction and advantage all as hereinafter described and claimed in the accompanying drawing in which:

Fig. 1 is a fragmentary view in side elevation of a portion of a wire stitching machine, provided with an anvil blade embodying my invention.

Fig. 2 is a plan view on an enlarged scale of an anvil blade embodying my invention shown detached.

Fig. 3 is a side elevation of Fig. 2.

Figs. 4 and 5 are sections on line 4—4 and 5—5 of Fig. 2.

Fig. 6 represents a fragmentary plan view of a modified form of my novel anvil blade.

Fig. 7 is a section on line 7—7 of Fig. 6.

Referring to the drawing in which like reference characters indicate like parts, 1 designates the body portion of my anvil blade which is provided with the holes 2 for the reception of bolts 3 which secure the anvil blade to the frame of a wire stitching machine 4.

The anvil blade is provided with a tapering, flattened head portion 5 which is bent upon itself at 6 to form the stitch supporting member 7 which is spaced from the head portion 5 as at 8, and which is provided with the concave, stitch deflecting recess 9, which is positioned below the stitch forming and driving head 10 of the stitching machine 4.

The operation is as follows: The outer edge of the end flap of a box is inserted into the slot 8 formed between the tapered head 5 and the stitch supporting member 7 and the box is then moved inwardly over the tapered

head 5 of the anvil blade. This pushes the end flap still engaged in the slot 8 inwardly into the end of the box and supports it immediately below the side wall of the box.

5 A stitch is then driven by the stitching head 10 through the side wall of the box and through the end flap to secure them together. The ends of the wire stitch or stapler are deflected inwardly in opposite directions by the

10 concaved recess 9. After the stitch has been made the box is moved towards the anvil blade until the edge of the end flap engaged by the slot 9, is released.

The tapered head portion 5 is shown in

15 the drawing on a greatly enlarged scale but in reality it is flat so that it may be conveniently inserted between the end flap and the side wall to which the end flap is to be stitched. The length of the head 5 or the slot

20 9 can be varied with different requirements. It is to be noted that the stitch is driven from the outside and that the oppositely deflected free ends of the stitch are inaccessible so that the stitch can not be removed and replaced.

25 It is further to be noted that my novel anvil blade is applicable to any conventional wire stitching or stapling machine since all such machines have an anvil to support the device while the stitch is driven.

30 In Figs. 6 and 7 I have shown a modified form of anvil blade wherein the slot 8 intermediate the head 5 and the stitch supporting member 7 instead of being cut along rectilinear lines to have a rectangular cross section as seen in Figs. 2 and 4, is cut along a

35 curved line 12 so that the slot 8 extends below or forms an undercut in the bottom of the head 5 as seen at 13. This produces a thin edge 14 (see Fig. 7) instead of the blunt edge

40 15 (see Fig. 4) thereby facilitating the insertion of the edge of the box flap to be engaged by the head 5 through the slot 8.

Having thus described my invention what I claim as new and desire to secure by Letters Patent, is:—

An anvil blade for a wire stitching machine comprising a body portion adapted to be secured to a machine, a front slotted stitch supporting portion adapted to engage the

50 flaps of a container to be stitched, said stitch supporting portion being tapered and bevelled to facilitate insertion thereof between said flaps with said container in the closed condition, and a stitch deflecting recess there-

55 in.
